Coty, Inc., a corporation of Delaware

Application July 8, 1946, Serial No. 131,360

Term of patent 14 years

(Cl. D80—9)

To all whom it may concern:

Be it known that I, Leon Cotnareanu, a citizen of the United States, residing in the city, county, and State of New York, have invented a new, original, and ornamental Design for a Perfume Bottle Holder or Similar Article, of which the following is a specification, reference being made to the accompanying drawing, forming a part thereof.

Fig. 1 is a front view of a perfume bottle holder or similar article, showing my new design;

Fig. 2 is a side view thereof;

Fig. 3 is a fragmentary view illustrating the lower rear thereof.

The essential features of my design reside in the portions shown in full lines. The bottle shown in broken lines in Figs. 1 and 2 is for illustrative purposes only.

I claim:

The ornamental design for a perfume bottle holder or similar article, substantially as shown and described.

LEON COTNAREANU.
